S. NARUNSKY

NONREFILLABLE BOTTLE

Original Filed Dec. 13, 1922

Inventor

Solomon Narunsky,
By E. Lattu Brumington

Attorney

Patented Sept. 29, 1925.

UNITED STATES PATENT OFFICE.

SOLOMON NARUNSKY, OF BALTIMORE, MARYLAND.

NONREFILLABLE BOTTLE.

Substitute for application Serial No. 606,562, filed December 13, 1922. This application filed September 18, 1924. Serial No. 738,425.

To all whom it may concern:

Be it known that I, SOLOMON NARUNSKY, a citizen of the United States, residing at Baltimore city, State of Maryland, have invented certain new and useful Improvements in Nonrefillable Bottles, of which the following is a specification.

This application is a substitute for application, Serial No. 606,562, filed December 10 13, 1922.

This invention relates to non-refillable bottles of that type having a valve which is so constructed and arranged that while it permits a free discharge of the contents of 15 the bottle, it seats if an attempt is made to force anything into the bottle, thereby preventing unscrupulous dealers from refilling the bottle after it has been emptied.

A bottle of the kind stated is disclosed in 20 Patent No. 1,227,648, dated May 29, 1917, and the present invention has for its object to devise certain improvements in the valve mechanism disclosed in this patent, as will be pointed out in the detailed description 25 appearing hereinafter, whereby the non-refillable feature is rendered more efficient and reliable in action.

In order that the invention may be better understood, reference is had to the accompanying drawing, wherein:

Figure 1 is a vertical section of the valve mechanism positioned within the bottle neck, and Figs. 2, 3 and 4 are perspective views of a valve-guard, a valve weight and guide, and 35 a valve detached.

Referring specifically to the drawing, 10 denotes the neck of an ordinary bottle formed with an internal shoulder 11 which serves as a seat to support the valve mechanism. This mechanism comprises the following parts:

In the bottle neck 10 is mounted a cylindrical pouring tube 12 having its lower end threaded for connection with a plug 13 provided with a fluid passageway 14 opening at 40 one end into the bottle and at the other end into the tube. The end of the plug which extends into the tube forms a seat for a valve 15 for closing the upper end of the 45 passageway opening into the tube. The valve body has side ribs 16 which space the same from the inner surface of the tube so that the liquid may flow past the valve when it is unseated and the bottle is inverted. 50 From the back of the valve rises a stem 17

on which is slidably mounted a sleeve-like weight member 18 which is so dimensioned and shaped that the liquid can also flow past the same when the valve is open and the bottle is inverted. The parts thus far 60 described are substantially the same as the tube, valve and weight disclosed in the patent hereinbefore referred to.

Above the valve stem 17, the tube 12 encloses a valve guard 19 having at the bottom a central cavity 20 to seat on the upper end of the valve stem. The side of the guard has an encircling groove 21 located intermediate the ends of the guard. The side of the guard also has longitudinal 70 grooves 22 which open at one end into the grooves 21, and at their other end into transverse grooves 23 in the bottom of the guard, said transverse grooves radiating from the cavity 20. Above the groove 21, the side of 75 the guard has longitudinal grooves 24 which open at one end into said grooves 21, and at their other end into grooves 25 located in crossed relation in the top of the guard. The grooves 22 and 24 are not in alinement 80 but are offset laterally relative to each other. The guard seats slidably in the tube 12, and it effectually prevents the insertion of a wire or other device for holding the valve 15 off its seat, thus frustrating attempts to refill the bottle. The guard extends completely across the tube 12 and is 85 in contact with the interior surface of the latter, which, together with the non-aligning relation of the grooves 22 and 24 makes it 90 impossible to get a wire or other device past the guard for disabling the valve 15.

When the valve 15 is unseated and the bottle is inverted, the liquid can freely pass the guard 19, the flow being by the way of 95 the grooves 22, 21, 24 and 25. Above the guard, the tube 12 has an internal shoulder 26 produced by here reducing the diameter of the tube, whereby the guard is prevented from slipping out of the tube.

The tube 12 is held in place within the bottle neck 10 by a cap 27, with a gasket 28 interposed between the same and the edge of the bottle mouth. A gasket 29 is also interposed between the interior surface of 105 the neck 10 and the outside of the tube, at its upper end.

I claim:

1. The combination with the neck of a bottle, of a pouring tube mounted therein,

- a valve seat at the inner end of the tube, a valve in the tube adapted to engage said seat and provided with an upstanding stem, and a valve guard slidably mounted in the
5 tube and loosely seated on the upper end of the valve stem, said guard having transverse grooves in its top and an external encircling groove in its side, and also side grooves extending from the bottom of the guard to the encircling groove and from the latter groove to the transverse grooves in the top of the guard, the first mentioned side grooves being out of alinement with the second mentioned side grooves, the aforesaid tube having an internal shoulder below
10 which the guard is located, and an external groove at its upper end portion and a gasket interposed therein and extending above the edge of the bottle mouth, and a cap provided on the bottle mouth for securing the tube in place within the bottle neck, substantially as described and for the purpose set forth.
2. The combination with the neck of a bottle, of a pouring tube mounted therein, a valve seat at the inner end of the tube, a valve in the tube adapted to engage said seat and provided with an upstanding stem, and a valve guard slidably mounted in the
15

tube and loosely seated on the upper end of 25 the valve stem, said guard having transverse grooves in its top and an external encircling groove in its side, and also side grooves extending from the bottom of the guard to the encircling groove and from the latter groove to the transverse grooves in 30 the top of the guard, the first mentioned side grooves being out of alinement with the second mentioned side grooves, the aforesaid tube having an internal shoulder below 35 which the guard is located, and an external groove at its upper end portion and a gasket interposed therein and extending above the edge of the bottle mouth, and a cap provided on the bottle mouth with said gasket 40 interposed between said cap and the edge of said bottle mouth for holding the said tube in place within said bottle neck, substantially as described and for the purpose set forth.

In testimony whereof I affix my signature.

SOLOMON NARUNSKY.
